ALBERT S. WILKINSON, OF PAWTUCKET, RHODE ISLAND.

Letters Patent No. 65,144, dated May 28, 1867.

IMPROVED HORSE-SHOE.

The Schedule referred to in these Letters Patent and making part of the same.

TO ALL WHOM IT MAY CONCERN:

Be it known that I, ALBERT S. WILKINSON, of Pawtucket, in the county of Providence, and State of Rhode Island, have invented a new and useful improvement in Hinge-Jointed Horse-Shoe; and I do hereby declare the following to be a full, clear, and exact description of the same sufficient to enable one skilled in the art to which the invention appertains to make use of it, reference being had to the accompanying drawing, which forms a part of this specification, in which—

Figure 1 is a top view of my invention.

Figure 2 is a side view of the same; and

Figure 3 is a rear view.

Figure 4 is a view of an elastic spring.

The object of this invention is to improve jointed expanding horse-shoes so as to overcome the present practical objections thereto; and allow the feet of the animal to expand under pressure, as nature designed; and it consists in having a continuous clip surrounding the horse's foot, together with a toe-clip and heel-clips of such form that the nail or screw-fastenings are dispensed with, and the shoe made an adjustable one, and also in making an elastic connection between the two heels of the shoe by means of a steel spring, or by other elastic material.

A C, in the accompanying drawings, represent the body of the shoe, the part C being hinged to A by the tapering pivot, g' , and this joint is placed on one side of the toe, so that a toe-clip, a , may be used. A continuous clip, $a e e'$, is employed, and the heel-clips, e , are provided with arms, e^2 , so formed as to hold the shoe to the foot in connection with the toe-clip a , so that no nail or screw-fastenings are required. L is an elastic connection connecting the two heels of the shoe, to hold them on the foot and allow lateral expansion thereof. The arms $e^2 e^2$ of the heel-clips are so formed as to reach up and curve in over the top of the coronet; and thereby hold the heel of the shoe to the foot, while the toe is held by the toe-clip a . A steel spring, L, fig. 4, having buttons, $l l$, upon its ends, is used to button the heels together, the buttons $l l$ being placed in the button-holes $k k$, fig. 3, by compressing the heel of the foot, so that when released the buttons engage with the slots on the inner edges of the button-holes, as seen in fig. 3, or the spring may be placed in the heel-clips by springing or expanding the spring. By these means the shoe is made adjustable, and may be readily removed or adjusted. In practice but one joint, g' , may be used, instead of two, as one joint admits of the expansion of the heel, and allows the shoe to be removed from or to be adjusted to the foot with as much facility as when the two or more are employed. With this mode of fastening, and when no nails are used as fastenings, but one joint, g' , is necessary, placed at the side of the toe-clip, as described. The elastic or spring connection between the heel-clip may be a rubber strap, or may be made of steel or other elastic material, operating substantially as represented. $d d$ represent "bar-clips" projecting inwardly beneath the heels.

Having thus fully described my invention, what I claim therein as new, and desire to secure by Letters Patent, is—

1. I claim an elastic or spring connection L, for connecting the heels of expanding shoes, substantially in the manner and for the purpose set forth.
2. In a jointed horse-shoe, as described, and having a continuous clip, I claim the toe-clip a and heel-clips $e e'$, provided with the projecting arms $e^2 e^2$, in combination with the elastic spring connection L, substantially as described.

ALBERT S. WILKINSON.
